UNITED STATES PATENT OFFICE.

CLARENCE Y. BOOTH, OF WILMINGTON, DELAWARE, ASSIGNOR TO ATLANTIC MANUFACTURING COMPANY, OF WILMINGTON, DELAWARE, A CORPORATION OF DELAWARE.

WEDGE FOR RUBBER HEELS.

Application filed August 23, 1923. Serial No. 658,924.

To all whom it may concern:

Be it known that I, CLARENCE Y. BOOTH, a citizen of the United States, residing in Wilmington, Delaware, have invented a 5 Wedge for Rubber Heels, of which the following is a specification.

This invention relates to devices adapted for insertion between the rubber heel and the adjacent lift for forcing out the rubber 10 heel above the worn parts and making the lower face of the heel substantially flat.

The object of the invention is to provide a device of this nature of novel and advantageous construction.

15 Another object of the invention is to provide means for retaining the device in place.

A still further object is to provide means for facilitating the operation of forcing the device into place between the rubber heel and 20 the adjacent heel portion.

In the attached drawings:

Figure 1, is a fragmentary side view of the heel portion of a shoe showing the manner in which the device is used;

25 Fig. 2, is a view in perspective of the reinforcing plate for one form of my device prior to the attachment thereto of the pad;

Fig. 3, is a section on the line 3-3, Fig. 2, but showing the resilient pad affixed to the 30 reinforcing plate;

Fig. 4, is a view in perspective of a modified form of reinforcing plate;

Fig. 5, is a section on the line 5-5, Fig. 4, but illustrating the pad affixed to the 35 reinforcing plate, and

Fig. 6, is a view in perspective of a further modified form of reinforcing plate within the scope of my invention.

With reference to the drawings, and particularly to Fig. 1, I have here illustrated the heel portion of a shoe, the reference numeral 1 indicating the visible fragment of the upper, 2 indicating the sole, and 3 of the heel lifts, usually of leather, secured to the heel lifts, usually of leather, secured to 45 the bottom one of which in the usual manner is a rubber heel 4. It is common for rubber heels to wear down at the back edge or at the side, as indicated by the dotted lines in Fig. 1, and heels so worn not only 50 are unsightly but are uncomfortable to walk upon. Although the main portion of the heel may be in good condition, it is ordinarily necessary, when the one small portion at the rear or side becomes worn, to replace

the heel with a new one. It has been suggested that a wedge of rubber or other material be inserted between the rubber heel and the bottom lift to force the worn portion of the rubber heel down, as illustrated in Fig. 1, in which a filler wedge made in 60 accordance with my invention and indicated by the reference numeral 5 is shown.

Prior to my invention, however, there has been no device of this type which is capable of being applied at home by the layman, and ordinarily it has been necessary, when these devices have been employed, to have them inserted by a cobbler. I have constructed a simple and efficient device of this type which 65 renders them easily applied and self-retained, no special retaining means being required.

With reference to Figs. 2 and 3, I preferably employ a substantially wedge-shaped pad 6 of rubber, although other material such as leather may be employed where this is found desirable. In order to reinforce the pad and to prevent its compression lengthwise when it is forced into the heel, as illustrated in Fig. 1, I affix to the pad a rigid 70 reinforcing element, preferably of light metal. One form of reinforcing element is illustrated in Fig. 2, which shows a flat arcuate plate 7 of the same outline and surface dimensions as one side of the pad 6. The plate 7, as clearly illustrated, is turned 75 over along that edge which corresponds to the forward pointed edge of the wedge-shaped pad, and as clearly illustrated in Fig. 3, the forward edge of the pad 6 lies in the back of this turned over portion 8 of the reinforcing plate, thereby entirely protecting 80 this edge. The pad is preferably vulcanized to the reinforcing plate 7, but these parts may be otherwise secured together, by 85 means, for example, of cement. It will now be apparent that a pad reinforced in the manner described may be easily driven or forced into place between the rubber heel 4 and the bottom lift 3 of the heel, the reinforcing plate preventing compression of the pad lengthwise, and the turned over edge 8 protecting the forward or pointed edge of the pad and preventing a possible tendency 90 of the pad to slip away from the reinforcing plate.

I further preferably provide the plate 7 with points or elevations 9 which by em-

bedding themselves in the rubber and in the leather of the heel insure retention of the pad in place. The most desirable means for forming these projections I have found to be by pressing out the metal of the plate, as clearly illustrated, and it will be noted that those sides of the projections which lie towards the forward edge of the wedge slant down to the plate so that each one of the 5 projections constitutes in itself a small wedge which while not materially interfering with the forward movement of the pad into place, precludes the possibility of the pad moving outwardly.

10 It may also be desirable to form projections on that side of the plate to which the pad 6 is affixed, as clearly illustrated, these projections tending to prevent relative movement or slippage between the pad and the plate while the pad is being forced into place in the heel.

15 In Fig. 4, I have illustrated a modification in which a reinforcing plate 11 is provided having at its forward edge extensions 25 12, 12. This plate may be pressed out of sheet metal, and is provided with a ridge 13 which, as shown in Fig. 5, lies directly in front of and protects the forward edge of the pad which, in this instance, is designated by the reference numeral 14. The plate 11 and the extensions 12 are preferably provided, as in the plate 7, with the pressed out points or projections 14.

20 In Fig. 6, I have illustrated a further modification of the reinforcing plate, in which the plate 15 formed with turned over forward edge 16, as in the plate 7, is also provided at the forward turned over edge with a plurality of apertures 17, said apertures being formed in the plate prior to the

turning over of the edge 16 and assisting in the turning over operation.

25 It will be apparent that the device may be applied with facility to the heel by inserting the forward edge at the desired point 45 between the rubber heel and the lower lift 3 and exerting a pressure or hammering upon the rear edge of the reinforcing plate. Where rubber or other material of which the pad proper is made is of the same color 50 as the rubber heel, the device is practically invisible and does not in any way destroy the neat appearance of the heel.

30 It will, of course, be understood that numerous modifications in the form of the reinforcing element are possible with no departure from the essential features of the invention.

I claim:

35 1. A filling-out wedge adapted for insertion between a rubber heel and the contiguous lift comprising a substantially wedge-shaped resilient element having affixed to and overlying one face thereof a rigid reinforcing member by means of 60 which the wedge may be driven into place, and projections on said member adapted to prevent dislodgment of said element.

40 2. A filling-out wedge adapted for insertion between a rubber heel and the contiguous 70 lift comprising a substantially wedge-shaped rubber pad having affixed thereto a rigid reinforcing member comprising a part lying along and in advance of the entering edge of said wedge, and projections on the 75 member having sides inclined toward the front of the wedge, substantially as described.

CLARENCE Y. BOOTH.
